US0D1006398S

(12) **United States Design Patent** (10) **Patent No.:** **US D1,006,398 S**
(45) **Date of Patent:** **** Dec. 5, 2023**

(54) **POCKET BAND**

(71) Applicant: **DRYMAX TECHNOLOGIES, INC.**,
Paso Robles, CA (US)

(72) Inventors: **William A. Blythe**, Paso Robles, CA
(US); **Charles R. Coffey**, Fyffe, AL
(US)

(73) Assignee: **DRYMAX TECHNOLOGIES, INC.**,
Paso Robles, CA (US)

(**) Term: **15 Years**

(21) Appl. No.: **29/757,763**

(22) Filed: **Nov. 9, 2020**

(51) **LOC (14) Cl.** **06-01**

(52) **U.S. Cl.**

USPC **D2/610**

(58) **Field of Classification Search**

USPC D2/610-611, 614, 621, 623, 747, 980,
D2/992

CPC A41D 20/00

(57) **CLAIM**

We claim the ornamental design for a pocket band, as shown and described.

DESCRIPTION

FIG. 1 is a first perspective view of a pocket band, showing our new design;

FIG. 2 is a second perspective view of the pocket band of FIG. 1 rotated 180 degrees;

FIG. 3 is plan edge view of the pocket band of FIG. 1;

FIG. 4 is plan edge view of the pocket band of FIG. 2;

FIG. 5 is a first side plan view of the pocket band;

FIG. 6 is a second side plan view of a pocket band;

FIG. 7 is a third side plan view of a pocket band;

FIG. 8 is a fourth side plan view of the pocket band;

FIG. 9 is an inside-out plan view of the pocket band of FIG. 5; and,

FIG. 10 is a plan view of the pocket band of FIG. 3 showing a pocket of the pocket band in an open configuration.

1 Claim, 5 Drawing Sheets
